UNITED STATES PATENT OFFICE.

ANKER PETERSEN, OF WINTHROP, MASSACHUSETTS.

WINDER FOR BRAIDING MACHINES.

Application filed August 16, 1922. Serial No. 582,163.

To all whom it may concern:

Be it known that I, ANKER PETERSEN, a citizen of the United States of America, and resident of Winthrop, in the county of Suffolk and State of Massachusetts, have invented new and useful Improvements in Winders for Braiding Machines, of which the following is a specification.

This invention relates to braiding machines of that type employed in the making of thread or cord such for example as is used in sewing shoes and is more specifically concerned with mechanism for drawing off and winding the braid as produced by the machine.

Sewing thread or cord employed in sewing shoes is usually supplied to the trade upon headless spools or quills, the thread mass being of cylindrical form with radial end faces. It is clear that the number of turns of thread upon a cop or thread mass of standard length will differ with the size of the thread, and as any given braiding machine may be called upon at different times to make thread of widely different sizes it is necessary to provide for varying the ratio of speeds of the traversing thread guide and the winding spindle, but such variation must not affect the tension under which the thread is wound upon the spindle, although, in order to provide a thread acceptable for sewing, it should be wound under a tension as nearly approaching its ultimate strength as can safely be maintained.

The principal object of the invention is accordingly to provide a braiding machine having winding mechanism capable of winding cops, or thread masses under heavy and uniform tension and having provision for changing the number of turns of the braided thread in each of the several layers of the thread mass in accordance with the size of the thread being braided.

In the accompanying drawings there is shown by way of example an embodiment of means suitable for attaining the above object and in such drawing:

Fig. 1 is a front elevation of the upper part of a braiding machine of well known type showing the winder mechanism of the present invention applied thereto:

Fig. 2 is a fragmentary elevation from the left side of Fig. 1 illustrating details of the winder mechanism; and

Fig. 3 is a vertical cross section on the line 3—3 of Fig. 1.

Referring to the drawings the numeral 1 indicates the stationary cam cylinder of a braiding machine of that type in which two series of carriers are caused to revolve in opposite directions. The carriers of the inner series are not herein illustrated but the rotating support 2 for the other series is shown with the carriers 3 mounted thereon. A frame 4 is mounted upon the base of the machine and bridges the operative parts thereof. This bridge frame has the depending, centrally disposed member 5 having a clamp for the braiding die at the point 6. The member 5 also supports a stub shaft 65 upon which a guide roll 7 turns, and also a shaft 8 upon which a take-up pulley 9 is mounted. At one side of the machine a vertical shaft 10 is arranged, and this shaft may be driven in any suitable manner from the driving shaft of the machine. The shaft 10 is provided with a pinion 11 meshing with a gear wheel 12 secured to a shaft 13 having bearings in the frame. Motion is transmitted from the shaft 13 by means of intermeshing gears 14 and 15 to a parallel shaft 16. The shaft 16 is provided with a pinion which meshes with an internal gear (not shown) upon the inner face of the take-up pulley 9, the arrangement thus far described being substantially like that disclosed in the patent to Peterson 1,413,773, April 25, 1922 to which patent reference may be had for a more detailed description of these parts. If desired the shaft 16 may 90 also drive a measuring wheel 17.

A sprocket wheel 18 is fixed to the shaft 16 and a sprocket chain 19 which engages this wheel drives a sprocket wheel 20 mounted to turn freely upon a shaft 21 having bearings in brackets 22 and 23 rising from the bridge frame 4. A clutch member 24 is fast to the shaft 21 and a tension spring 25 surrounding the shaft and adjustable by means of a nut 26 presses the wheel 20 into contact with the clutch member so as normally to impart movement to shaft 21, slight slipping of the parts being permitted however as the diameter of the thread mass increases. The shaft 21 constitutes the winding spindle and has a member 27 of somewhat larger diameter mounted thereon or forming a part thereof, this member preferably being somewhat resilient and serving for the reception of the quill or other support upon which the thread mass 28 is wound. A pinion 29 is removably keyed to

the shaft 21 and meshes with a change gear 30 removably keyed to a counter-shaft 31 which is mounted to turn in bearings in a frame comprising the spaced arms 32, and 5 33 and the longitudinally extending web member 34. The side members of the frame are pivoted to swing upon a shaft 35 mounted in bearings at the lower portion of the bracket 22 and in a bracket 36 respectively. 10 A lug 37 projects from the central part of the web 34 and the upper end of a link 38 is pivotally secured to this lug, the lower end of the link passing through an opening in a bracket 39 projecting rearwardly from 15 the member 34. The lower part of the link is screw-threaded as shown at 40 and a pair of nuts 41 and 42 engage such screw-threaded portion at the opposite sides of the bracket 39. With this arrangement the 20 position of the frame with the shaft 31 may be accurately adjusted by means of the nuts 41 and 42.

A pinion 43 is fast to the opposite end of the shaft 31 and meshes with a pinion 44 fast to a shaft 45 aligned with shaft 35 and mounted to turn in bearings in a pair of spaced brackets 46. The shaft 45, at that portion which lies intermediate the brackets 46, is provided with a reversely pitched cam 30 groove or worm 47 of suitable configuration. A pin 48 engages this cam groove or worm, being carried by a sleeve or nut member 49 forming a part of the thread guide carriage and which surrounds the threaded portion 35 of the shaft. This sleeve or nut member is provided at opposite ends with ears 50, and 51 respectively which project forwardly and into a slot provided between a pair of bars 52, and 53 which unite the brackets 46. 40 Preferably antifriction means such as the ball bearing ring 49^a carried by a stud projecting from the nut 49 is arranged to engage one of the bars 52 or 53 to prevent undue wear and resistance to movement. A 45 thread guide frame is pivotally secured to the lugs 50, 51 by means of pins such as 57. This thread guide frame comprises a pair of spaced lugs 55 and 56 connected by cross bars 58 and 58^a. The free extremities of 50 the lugs 55 and 56 support a shaft 59 upon which a grooved guide wheel or roll 60 is mounted to turn.

The operation of the braiding machine forms braid at the point 6, and this braid 55 after making several turns about the guide pulley 7 and the take-up wheel 9, passes over a pulley 61 mounted in a bracket 62 at a suitable elevated point, thence down beneath the grooved roll 60 and then to the 60 winding thread mass upon the spindle member 27. During the operation of the braiding machine the shaft 10 is rotated, thereby 65 rotating the shaft 21. By means of the connections described, the shaft 45 is positively turned in time with the driving of the

winding spindle. The thread guide carriage is thus caused rapidly to reciprocate back and forth longitudinally of the spindle thereby laying the braided thread in close coils and building up a warp wound 70 thread mass of substantially cylindrical form having its coils so disposed that the thread mass is self-sustaining making a headed spool unnecessary.

With the employment of the drive above 75 described it is possible by properly tensioning the spring 25 to wind the thread under very heavy tension, this being highly desirable in a thread which is to be used for machine sewing as in order to avoid kinking of the thread on its way to the needle it is necessary that the thread upon the spool or bobbin be wound under a tension approaching its ultimate strength. If it be desired to braid and wind thread of widely 80 different sizes, it is evident that a positive and unvariable drive connection would prevent the proper laying of all the different sizes to form a self-sustaining and compact thread mass. To permit threads of varying 85 sizes to be wound, the swinging frame comprising the members 32, 33 is employed. With this arrangement it is possible to remove one or both of the gears 29 and 30 and to substitute therefor gears of any other 90 desired size, the adjustability of the frame permitting the new gears to be brought into proper engagement. By properly selecting the diameter of the gears 20 and 30 almost any desired ratio of rotation of the spindle 95 and the traverse shaft 45 may be secured, thus permitting yarn of any ordinary size to be wound under high tension into a compact mass of a self-sustaining character 100 without necessitating the dismantling of the apparatus and without any substantial loss of time.

What I claim and desire to secure by Letters Patent of the United States is:

1. In a braiding machine having a main 110 drive shaft, braid forming mechanism and a frame extending transversely across the latter, the combination with the braid forming mechanism of a winding spindle journaled in said frame, means including a friction clutch for transmitting movement from the drive shaft to the spindle, a traverse cam shaft also journalled in said frame, a swing frame pivotally mounted upon said first frame, a shaft carried by the swing frame, a pair of gears carried by said shaft, one of said gears meshing with a gear secured to the cam shaft, and the other gear meshing with a gear secured to the spindle.

2. In a braiding machine having a main 125 drive shaft, the combination with the braid forming mechanism of a winding spindle, connections between the drive shaft and the spindle for driving the latter, a traverse actuating shaft substantially parallel to the 130

- spindle, a frame arranged to turn about an axis aligned with that of the shaft, a shaft journalled in said frame, said shaft having a pair of gears secured thereto, one of said 5 gears constantly meshing with a gear fast to said traverse actuating shaft and the other of said gears being engageable with a gear fast to the winding spindle.
3. In a braiding machine having a main 10 drive shaft, the combination with the braid forming mechanism of a winding spindle, a traverse actuating shaft substantially parallel to the spindle, connections between the drive shaft and the spindle for driving the latter, said connections including frictionally engaging parts, a frame pivoted to turn about an axis aligned with the axis of said shaft, a counter-shaft journalled in said frame, a gear fixed to one end of said shaft, 15 said gear meshing with a gear fixed to the actuating shaft in all positions of the frame, and a pair of intermeshing change gears removably secured to the counter shaft and spindle respectively and constructed and arranged to be interchanged with other gears 20 for varying the ratio of speed of the spindle and traverse actuating shaft.
4. In a braiding machine having a main drive shaft, the combination with the braid 25 forming mechanism of a winding spindle and a traverse actuating shaft, connections between the drive shaft and spindle for driving the latter, a frame having spaced end members rigidly secured together, a shaft 30 upon which said end members are pivoted to turn, a counter shaft journalled in the respective end members, gears carried by the counter shaft and meshing respectively with gears upon the spindle and traverse actuating shaft, and an adjustable link secured to 35 the frame for determining the position thereof.
5. In a braiding machine having a main drive shaft, the combination with the braid 40 forming mechanism of a winding spindle and an actuating shaft, means including a friction clutch for transmitting movement from the drive shaft to the spindle, a swinging frame having a countershaft journalled 45 therein, said countershaft having gears intermeshing with gears fixed upon the spindle and traverse actuating shaft, respectively, a link pivoted to said frame, said link having a screw threaded portion, and means 50 adjustably engaging said threaded portion for determining the angular position of the frame.
6. In a braiding machine having a main drive shaft, the combination with the braid- 55 ing mechanism of a winding spindle and a traverse cam shaft, means including a friction clutch for transmitting movement from the drive shaft to the spindle, a swinging frame having a countershaft journalled 60 therein, said shaft having gears intermesh- ing with gears on the spindle and cam shaft, respectively, a link pivotally secured to the frame, said link being screw threaded adjacent to its free extremity and passing through an opening in a bracket fixed to the machine 65 frame, and a pair of nuts engaging the threaded portion of said link and disposed respectively upon either side of the bracket whereby to permit adjustment of said frame to accord with the size of the intermeshing 70 gears carried by the spindle and counter- shaft.
7. Winding mechanism for braiding machines comprising a frame, a winding spindle journalled therein, a drive shaft, means 75 including a friction clutch for transmitting movement from the drive shaft to the spindle, a traverse cam shaft also journalled in said frame, a swing frame pivotally mounted upon said first frame, a shaft carried by the swing frame, and a pair of gears carried by said shaft, one of said gears meshing with a gear secured to the cam shaft, and the other gear meshing with a gear 80 secured to the spindle.
8. Winding mechanism comprising a drive shaft, a winding spindle, connections between the drive shaft and the spindle for driving the latter, a traverse actuating 85 shaft substantially parallel to the spindle, a frame arranged to turn about an axis aligned with that of the shaft, a shaft journalled in said frame, said shaft having a pair of gears secured thereto, one of said 90 gears constantly meshing with a gear fast to said traverse actuating shaft, and the other of said gears being engageable with a gear fast to the winding spindle.
9. Winding mechanism comprising a drive shaft, a winding spindle, a traverse 95 actuating shaft substantially parallel to the spindle, connections between the drive shaft and the spindle for driving the latter, said connections including frictionally engaging parts, a frame pivoted to turn about an axis aligned with the axis of said shaft, a counter-shaft journalled in said frame, a gear fixed to one end of said shaft, said 100 gear meshing with a gear fixed to the traverse actuating shaft in all positions of the frame, and a pair of intermeshing change gears removably secured to the counter shaft and spindle respectively and constructed and arranged to be interchanged with other 105 gears for varying the ratio of speed of the spindle and traverse actuating shaft.
10. Winding mechanism comprising a drive shaft, a winding spindle, connections between the drive shaft and spindle for driving the latter, a frame having spaced 110 end members rigidly secured together, a shaft upon which said end members are pivoted to turn, a counter shaft journalled in the respective end members, gears carried by the spindle and traverse actuating 115 shaft.

shaft, and an adjustable link secured to the frame for determining the position thereof.

11. Winding mechanism comprising a main drive shaft, a winding spindle, a traverse actuating shaft, means including a friction clutch for transmitting movement from the drive shaft to the spindle, a swinging frame having a countershaft journaled therein, said countershaft having gears intermeshing with gears on the spindle and cam shaft, respectively, a link pivotally secured to the frame, said link being screw threaded adjacent to its free extremity and passing through an opening in a bracket fixed to the machine frame, and a pair of nuts engaging the threaded portion of said link and disposed respectively upon either side of the bracket whereby to permit adjustment of said frame in accordance with the size of the intermeshing gears carried by the spindle and countershaft.
12. Winding mechanism comprising a main drive shaft, a winding spindle, a traverse cam shaft, means including a fric-

tion clutch for transmitting movement from the drive shaft to the spindle, a swinging frame having a countershaft journaled therein, said shaft having gears intermeshing with gears on the spindle and cam shaft, respectively, a link pivotally secured to the frame, said link being screw threaded adjacent to its free extremity and passing through an opening in a bracket fixed to the machine frame, and a pair of nuts engaging the threaded portion of said link and disposed respectively upon either side of the bracket whereby to permit adjustment of said frame in accordance with the size of the intermeshing gears carried by the spindle and countershaft.

Signed by me at Boston, Massachusetts, this ninth day of August, 1922.

ANKER PETERSEN.
